PHOTOGRAPHIC DEVELOPING MACHINE

Samuel Hershberg, Brooklyn, N. Y.

Application September 21, 1934, Serial No. 744,886
Renewed May 12, 1939

25 Claims. (Cl. 95—90)

This invention relates to a photographic developing machine forming a unit in the system of photography embodied and described in your applicant's application for patent, filed in the United States Patent Office on September 15, 1934, bearing Serial Number 744,225.

The main object of this invention lies in the provision of a photographic developing machine in which all of the steps and operations, from the time an exposed sheet of sensitized material is received within the machine until the finished print is delivered by the machine, are substantially automatic.

Another object of the invention is the provision of a developing machine whereby operating costs are reduced to a minimum owing to: saving of space by virtue of compact and cooperative arrangement of the various sub-assemblies; saving in the cost of chemicals by eliminating inter-tank pollution in said developing machine; saving of labor costs by the substantially automatic operation of the machine, and the manipulation and transfer therethrough of the sensitized material; the production of a higher average of perfect prints, the result of precise timing of the development steps and exact mechanical manipulation.

A still further object of the invention is the provision of structure permitting the lightproof communication between this developing machine and a camera, capable of movement.

Still another object of this invention is the provision of structure whereby individual sheets of sensitized material are manipulated through the developing machine without the use of backing-pieces or frames to reinforce the said sheets or the necessity of feeding the developing machine with long continuous strips of sensitized material.

These objects and other incidental ends and advantages will more fully appear in the description below and as pointed out in the appended claims.

In the accompanying drawings: Figure 1 is a left side view in elevation of the developing machine with the side wall of the casement thereof removed showing various sub-assemblies mounted on a shelf therein as well as means for moving, along the upper surface of the casement a carriage adapted to form a lightproof entrance to the developing machine as well as furnish a means for communication with a camera which may be operated simultaneously and in conjunction with the said developing machine.

Figure 2 is a right side view in section, being

partly in elevation, along the line 2—2 of Figure 3.

Figure 3 is a view in section along the line 3—3 of Figure 2, being partly broken away and showing a plan view of the developing machine.

Figure 4 is a sectional view of Figure 3, along the line 4—4 thereof, showing drying mechanism, mechanism for feeding sensitized paper to a spider arm and mechanism for releasing said paper to said drying mechanism.

Figure 5 is a sectional view of Figure 4 along the line 5—5 thereof and shows mechanism for feeding the sensitized paper to a spider arm.

Figure 6 is a sectional view of Figure 2 along the line 6—6 thereof and shows the mechanism 15 for transmitting motions to the paper carrying spider mechanism.

Figure 7 is a sectional view of Figure 3 along the line 7—7 thereof and shows the developing machine timing device and the heater unit switch 20 of the drying mechanism.

Figure 8 is a sectional view of Figure 3 along the line 8—8 thereof and shows the developing machine motor switch.

Figure 9 is a sectional view of Figure 3 along the line 9—9 thereof and shows the developing machine timing device.

Figure 10 is a sectional view partly in elevation along the line 10—10 of Figure 7 and shows the developing machine timing device.

The framework of the developing machine comprises a pair of longitudinal base bars 20, front vertical uprights 23, intermediate vertical uprights 24 and rear vertical uprights 25, the said vertical uprights supporting at the tops thereof the inclined upper frame members 22. Intermediate the height of the front vertical uprights 23, there is supported a horizontal shelf 21 within the said frame work. Panels enclose the frame work on the front, rear and side walls, while a base plate is provided to form the flooring of the apparatus, these panels and base plate forming a casing, the remaining top opening being covered by movable light proof curtains 136 and 136', serving as an upper wall of said casing; the panels and base plates above mentioned not being shown in the drawings specifically by numerals.

The inclined upper frame members 22 serve as ways or tracks for carrying a camera, movable with relation to this developing machine. The camera 351 indicated by the dot dash lines on Figure 1, may be of any suitable type adapted to discharge exposed sheets of sensitized material into the developing machine casing, of which the right side and front and rear panels or walls are 55

shown, the left side panel being shown removed to better display the mechanism therein. The camera 351 penetrates and extends at the lower end thereof through a base member 133 which constitutes a movable aperture with relation to the developing machine casing or chamber, the latter being of light-proof construction. The top surface of base member 133 is cut out for the admission of the camera 351, while the side walls of said base member depend perpendicularly from the top surface thereof and are perpendicular to each other, leaving the bottom open.

The base member is supported by four wheels 134 mounted on the inner surfaces of the longitudinal walls of said member, the bottom edges of these walls being in a plane parallel to and below the plane of the inclined upper frame members 22. Wheels 134 are provided with peripheral flanges which engage the flanged inner edges of the frame members 22 and thereby prevent transverse displacement of the base member 133 as wheels 134 ride along the inclined tracks therefor. These tracks are formed by the said inwardly projecting flanges from the upper edges of the frame members 22.

Numeral 725 indicates a pair of longitudinal and inclined racks affixed to the inner surfaces of inclined frame members 22 at the lower edges thereof. Racks 725 are engaged by a pair of pinions 726 mounted on a transverse shaft 727 which is trunnioned at the terminals thereof in the longitudinal walls of base member 133. Pinions 726 mesh with a pair of pinions 728 carried by a shaft 729 which is disposed similarly to shaft 727. Pinions 728 mesh with smaller pinions 730 mounted upon a shaft 731 which is trunnioned in the longitudinal walls of base member 133 and projects therethrough to have affixed to one terminal thereof a handwheel 732. It will be seen upon a reference to Figure 1 wherein one each of the pinions 726, 728 and 730, and racks 725 are shown, that revolution of handwheel 732 will cause base member 133 to ride up and down the inclined tracks upon which wheels 134 revolve. The manipulation of the base member 133 up and down the inclined track is facilitated by means of a counterweight 142, riding within an upright casing 143, the said weight being connected to the base member 133 at the rear transverse wall thereof by a chain 140, the sprocket 141 supporting said chain above the upright casing 143.

Situated between the inclined members 22 and below the inwardly projecting flanges thereof are two flexible light-proof curtains 136 and 136', the free ends of said curtains being affixed to base member 133 at the rear and front walls thereof respectively, the said curtains 136 and 136' traveling with the movements of the base member 133. Curtain 136 rides over rollers 137, and 138 and is maintained taut by spring roller 139; while curtain 136' rides over rollers 137' and 138' and is maintained taut by spring roller 139'.

The camera 351 is adjusted by moving the same pivotally in a vertical plane by means of a handwheel 742, and in a horizontal plane by means of another handwheel 750, mounted on an axle 751 therefor.

The developing machine is provided with a motor 30, which is positioned rearwardly of the framework and supported on the floor thereof by a pedestal 31. The main shaft 32 of motor 30 runs transversely of the framework and revolves at 800 revolutions per minute. Shaft 32 communicates with a speed reduction gear box 33

which reduces the speed to 43 R. P. M. which latter speed is transmitted by means of a longitudinal main power transmission shaft 34. The said shaft is supported along the length thereof by means of a plurality of uprights shown best in Figure 2 of the accompanying drawings.

Disposed along the vertical central axis of the developing machine and mounted between the flooring and a bracket 50 is a central axle 48 penetrating shelf 21. The said central axle 48 is rotatable, being mounted in its lower support bearing 39 and in its upper bearing 49, the said bearing 49 being affixed to bracket 50. The lower support bearing 39 is a part of plate 38 which latter plate is integrally attached to a high speed oscillatory cam upright support 45. Numeral 46 indicates the lower portion of upright support 45 and is provided with a transverse orifice serving to confine the reciprocating aligning pin 42, a compression spring 43 and a retaining plug 44. Opposite aligning pin 42 is a toothed wheel 40 keyed to shaft 48 by pin 41 and is adapted to accurately position shaft 48 at 36 degree intervals of rotation. Since reciprocating aligning pin 42 projects off spring 43, any slight variation from a 36 degree interval of toothed wheel 40 is corrected.

The central axle 48 is provided with a sleeve 53 keyed thereto and adapted to rotate therewith, the said rotation being effectuated by the maximum upward vertical displacement of sleeve 53, the said keying permitting free vertical movement of sleeve 53 along the central axle 48. The upper limit of sleeve 53 is expanded to form flange portion 55 on which is integrated a spider hub 56. Superposing and integral with said spider hub 56 is a face gear 57, the flange portion 55, the spider hub 56 and the face gear 57 all being provided with aligned orifices for the penetration therethrough of the central axle 48.

When sleeve 53 is forced to its upward and vertical maximum position, a pivotal pawl 51 mounted on bearing 49 in assuming a forced horizontal position by articulating with one of the teeth of the face gear 57, causes a 36 degree anti-clockwise rotation of sleeve 53. It is this 36 degree rotation that aligning pin 42 serves to maintain and correct.

The lower limit of sleeve 53 is provided with an expanded portion to provide a lower flange 54, the under face of said lower flange 54 serving as the bearing surface for a pair of rollers 71, the said rollers 71 being mounted on the forked end 69 of sleeve actuating lever 63. Sleeve actuating lever 63 is pivotally mounted at the other end thereof to a bracket 66 affixed to a frame work portion 68. The lever 63 is provided with elevating cam surface 64 and lowering cam surface 65, both of said surfaces being on the underside thereof. Cooperating with the said cam surfaces is a follower arm 74 having mounted on the outer end thereof a roller 72 riding along the cam surfaces. Follower arm 74 is keyed to a shaft 75 which latter is keyed to a worm gear 76. Said gear 76 engages with a worm 77 keyed to shaft 34. Gear wheel 76 revolves at the rate of approximately one revolution every sixty seconds and in so doing brings about a vertically reciprocating motion to sleeve 63 during a ten second period of each revolution, the first five seconds being taken up in elevating sleeve 53 and the second five seconds being taken up in causing the sleeve to drop through the action of gravity. In order to facilitate the transmission of motion from lever 63 to sleeve 53, the operative end of said

lever is bifurcated to form a yoke portion 69, having inwardly projecting opposed pivots 70 upon which are mounted a pair of rollers 71 as referred to hereinbefore.

A constantly rotating cam 78 is in frictional engagement with the undersurface of lever 63 at a point adjacent to the yoke portion 69 thereby causing a rapid vertically reciprocatory motion in sleeve 53. These oscillations occur at a frequency of approximately forty three per minute and are adapted to cause an agitation of solutions in the tanks containing solutions as will herein-after be more fully described. The said cam 78 is keyed to shaft 79 which shaft is journaled in bearings 79'. These bearings 79' are mounted in slots or guideways formed in the two arms of the U shaped portion 47 of the high speed oscillatory cam upright support 45, the said U shaped portion constituting the upper part of the said upright support 45. Since the bearings 79' are capable of vertical displacement within the said guideways, they are maintained in normal position by springs 78' adjustably mounted in the bases of the said guideways. Shaft 79 at one end thereof is provided with a sprocket 95 which latter is connected by means of a chain 94 to another sprocket 84. Sprocket 84 is affixed to one end of a short shaft which penetrates a mounting therefor 85, the said short shaft having at the other end thereof a bevel gear 86, which latter bevel gear meshes with another bevel gear 87 keyed to shaft 34. In order to facilitate the loading and unloading of sensitized material into clips attached to spider arms as will herein-after be described, it is necessary that the rapid vertically reciprocal motion of sleeve 53 be suspended during that period, and this suspension is accomplished by forcing cam 78 out of engagement with sleeve actuating lever 63. Resting on the projections of shaft 79 beyond the arms of U shaped portion 47, as best shown in Figure 6 of the accompanying drawings, are two arms 80 of a lever 82, the said lever being pivoted intermediate the length thereof at pin 81, the opposite end of said lever 82 being provided with a mounted roller 83 thereon. Pin 81 is mounted in a U shaped extension of the upright 90, the said upright serving also as a mounting for a shaft 89 to which shaft 89 is keyed cam 88. Cam 88 is rotated at a speed of approximately one revolution per minute by means of the sprocket 91 which is affixed to one end of the shaft 89, said sprocket 91 being connected by a chain 92 to another sprocket 93, the latter sprocket 93 being keyed to shaft 75 of worm gear 76. Because roller 83 is held in contact with cam 88 by the upward pressure of springs 78', lever 82 acts as a follower for cam 88 and for a predetermined period during each complete revolution of worm gear 76 cam 78 is depressed out of contact with sleeve actuating lever 63 by the downward movement of the arms 80 of lever 82.

The shaft 75 for worm gear 76 is supported by four bearing uprights 97, 97', 98 and 99, the said uprights forming vertical projections of a base plate 96. The same shaft 75 operating transversely of the main power transmission shaft 34 and deriving its rotation from the worm gear 76 thereon, as best shown in Figure 6 of the accompanying drawings, near the end opposite worm gear 76 is provided with a face cam 100 having cut in the face thereof a groove 101, said groove being annular and off center relative to shaft 75 so that a pin 102 riding within the aforesaid groove and affixed to the rear end of a rack

bar 103 causes the said rack bar 103 to reciprocate longitudinally within a guide groove formed with grooved guide member 104. The grooved guide member 104 is affixed to an upright indicated by numeral 105. The rack bar 103 is provided with a plurality of teeth 106 which mesh with a pinion 107 keyed to the control spindle of a known cylindrical surface valve 108. Valve 108 is located in a main water supply line designated by numeral 109. From a reference to Figure 6, it will be seen that with each single revolution of transverse shaft 75 the valve 108 will go through a cycle of opening and closing thereby allowing a definite amount of water to enter from supply pipe 109 into a connecting pipe 111 thence into a circular distribution pipe 110 and thence through a plurality of discharge pipes 110' as best shown on Figure 2 of the accompanying drawings. These discharge pipes 110' serve to maintain a constant level of water in water containing finishing tanks, the latter to be herein-after more fully described.

Mounted on transverse shaft 75 and adjacent to the face cam 100 is a keyed sprocket 112 which is connected by means of chain 113 to a sprocket 114, the said sprocket 114 being keyed to a known cylindrical surface valve 115 as best shown in Figure 3. The said valve 115 is of a quadruple type simultaneously controlling four distinct chemical solution supply pipes 117', 118', 119' and 120'.

Concentric with central axle 48 and supported by horizontal shelf 21 is an annular trough 121 having an outer wall 122 and an inner wall 123 having a segment removed at the front thereof as best seen in Figure 3 of the accompanying drawings. The said trough 121 is provided with a drain opening 121" communicating with a drain pipe 121' which latter serves to carry off liquids which have overflowed from finishing tanks 40 to be herein-after described. Set in the floor of the annular trough 121 are a plurality but preferably nine finishing tanks radially disposed thereon as best seen in Figure 3 of the accompanying drawings. Normally the tanks are relatively positioned so that the sensitized material in progressing through the development process is immersed in all nine tanks consecutively commencing with tank 124 containing developer, tank 125 containing water, tank 126 containing the 50 bleaching solution, tank 127 containing water, tank 128 containing clearing solution, tank 129 containing water, tank 130 containing the re-developing solution, tank 131 containing water, and tank 132 containing water or a suitable hardening solution for hardening the emulsion on the print to avoid the peeling thereof when transferred to the drying mechanism, then pipe 110' to tank 132 is closed.

Referring back to discharge pipes 110', it is 60 now seen how tanks 125, 127, 129, 131 and 132 maintain a constant level therein by the water supply pipes functioning during the operation of the mechanism and the draining of overflow water by pipe 121'.

Positioned above the main driving motor 30 is a supported housing 116 containing chemical solution supply tanks 117, 118, 119 and 120. Tank 117 contains developing solution, tank 118 contains bleaching solution, tank 119 contains clearing solution, tank 120 contains redeveloping solution, the said solutions being fed through the units of the quadruple type of valve 115, thence through chemical solution supply pipes 117', 118', 119' and 120', and thereby into tanks 124, 126, 65 70 75 80 85 90 95 100 105 110 115 120 125 130 135 128 and 130 respectively. The quadruple type of valve 115 is capable of adjustment so that the rate of flow therethrough of the various solutions may be synchronized with the amount of evaporation, chemical and physical consumption and sloppage. Since the control of valves 108 and 115 is derived from the motion of the main power transmission shaft 34, a timing mechanism to be hereinafter described cuts off the supply of current to the 10 driving motor 30 at a time when the valves 108 and 115 are in a closed position thereby preventing waste of water and chemical solutions automatically when the developing unit is not in operation.

15 The spider hub 56, as has been before described, is provided with a plurality of arms, but preferably 10 as is shown in Figure 3, the said arms being designated by numeral 60, being radially disposed and each being provided with a clip for 20 holding the sensitized material, the said clip being designated by numeral 58.

Now will be described the mechanism for feeding the previously exposed sensitized paper from the entrance therefor to clips 58 just above mentioned. 145 represents a conveyer being either gravity acting or driven, but in the present embodiment of the invention, the conveyer is represented as being a long trough substantially U-shaped in cross-section and being mounted by hangers 144 and 144', said hangers depending from inclined upper frame member 22, the said conveyer 145 being parallel to the said upper frame member 22. The purpose of the conveyer is to receive a sheet of previously exposed sensitized material, which has been cut and dropped on to the said conveyer by the camera unit. The sensitized material is mounted in the form of a roll in the camera unit, and the cutting results in the production of a definite and uniform size 40 of sheet of sensitized material, the size being adapted to the proportions of the camera and developing units.

Plates 26 and 27, situated in the central and forward portion of the developing unit constitute 45 the frame work for the feeding and control mechanism or assembly which transports the previously exposed sensitized material from conveyer 145 to one of the clips 58, the said assembly being best shown in Figures 2, 3 and 5 of the accompanying drawings. Numeral 146 represents 50 a continuous belt forming a flat conveying surface and being supported at one end by a driven roller 147 and on the other end by a driving roller 148, the said rollers 147 and 148 being supported respectively by bearings depending from 55 plate 27, the said bearings not being numerically designated in figures of the drawings. Driving roller 148 derives its motion from main driving shaft 34 by means of a sprocket 149 on an extension of the driving roller 148, the said sprocket 149 being connected to sprocket 151 on the end of the main driving shaft 34 by means of sprocket chain 150. Depending from the upper plate 26 are two spaced vertical guideway plates 154 and 60 155, the latter guideway plate 155 being curved toward plate 154 to form a mouth opening in which is mounted a vertical driving roller 164. Frictionally engaging driving roller 164 is another roller 167, the last two rollers cooperating 65 to draw between them in the direction indicated by the arrows on Figure 5 the sensitized material. Since the sensitized material comes from a roll in the camera unit, the curl of each sheet is taken advantage of so that the sensitized material up until the time it enters between rollers

164 and 167 is handled as a resilient semi-cylinder. Thus, when the sensitized material is discharged from the conveyer 145 upon moving belt 146, it alights on the base of the semi-cylinder rather than on the side thereof maintaining a vertical position thereby entering rollers 164 and 167 edgewise. The sensitized material having been drawn between rollers 164 and 167 now enters a semi-circular guideway formed by two curved plates, 156 and 157 and thence 10 between a second pair of rollers 170 and 173; thence into a straight guide-way formed by flat-walled plates 158 and 159. From the said straight guide-way, the sensitized material is drawn between a third set of rollers 175 and 28 and then 15 deposited within the guide-way chamber formed by flat-walled plates 160, 161 and 162 where it comes to rest. The sensitized material up to this point in its travel has been in constant motion owing to the fact that the intervals between 20 the sets of rollers 164, 167, 170, 173, 175, 28 have all been less than the length of the sheet of sensitized material. The interval between the pair of rollers 175, 28 and the pair of rollers 188, 185 is longer than the length of the sheet of sensitized material so that the said sheet comes to rest within the chamber 160, 161 and 162 because of the fact that it ceases to be propelled by contact with any moving rollers. Numeral 205 is a driving roller rotating in a direction 30 indicated by the arrow thereat and adapted to project within the chamber 160, 161 and 162 to contact with the sensitized material resting therein and thereby to move the said sensitized material toward a pair of rollers 188, 185. The 35 said rollers 188, 185 having engaged the sheet of sensitized material serve to continue the movement of the material into the open jaws of one of the clips 58, which latter has been positioned directly opposite and outside of the line of contact of rollers 188, 185, the synchronous positioning of the clip opposite the pair of rollers 188, 185 and the synchronous positioning of the roller 205 against the sensitized material being controlled by mechanism to be described below. 40

Sets or pairs of rollers 164—167, 170—173, 175—28 and 188—185 together with single roller 205 derive their motion interrelationally. The said four sets of rollers are mounted on spindles journalled between plates 26 and 27, the said 45 spindles being suitably spaced from each other. Roller 164 is mounted upon spindle 165, said spindle projecting upwardly through plate 26 and having affixed to the said projection a pinion 166 and immediately thereabove a sprocket 166'. 50 Roller 167 is mounted upon spindle 168 and is provided with a similar projection having affixed thereon a pinion 169 and immediately thereabove a sprocket 169'. Pinions 166 and 169 mesh with each other. Sprocket 169' is connected by means of sprocket chain 172' to sprocket 172, said sprocket being affixed to the upper end of spindle 171 upon which is mounted the roller 170. Roller 173 is driven by contact with roller 170 so that the spindle 174 upon 55 which roller 173 is mounted terminates at the upper end thereof flush with upper plate 26.

Sprocket 166' is connected by means of chain 180 to sprocket 179, said sprocket being affixed to the upper end of spindle 29, said spindle having mounted thereupon the roller 28. Affixed to spindle 29 immediately above upper plate 26 is a sprocket 177 which is connected by means of chain 216 to sprocket 181 which in turn is affixed to the upper end of vertical shaft 182. 70 75

Shaft 182 is journaled at the upper end thereof in an orifice in upper plate 26 and at the lower end in an inverted L-shaped upright support 182', the latter being an extension of the foremost bearing support of main driving shaft 34, as best shown in Figure 3 of the drawings. Affixed to vertical shaft 182 at the lower end thereof and below support 182' is a bevel gear 183 which meshes with a bevel gear 184, said latter bevel gear being keyed to the main driving shaft 34. Affixed to shaft 29 between sprocket 179 and sprocket 177 is a sprocket 178 which is connected by means of a chain 196 to a sprocket 195. Sprocket 195 is affixed to a spindle 192, the said spindle being journaled in orifices in upper and lower plates 26 and 27, the upper projection of the said spindle having mounted thereon and against the upper face of upper plate 26 a pinion 197, said pinion being positioned directly below sprocket 195. Above sprocket 195 and affixed to spindle 192 is a sprocket 193 which is connected by chain 194 to sprocket 187, the said sprocket 187 being affixed to spindle 186 at a point above upper plate 26, the said spindle serving as a mounting for roller 185. Opposite pinion 197 and meshing therewith is a pinion 198, said pinion 198 being affixed to a spindle 200, said spindle 200 being free to revolve within a sleeve member 200'. The sleeve member 200' is journaled between plates 26 and 27 and projects therethrough. Extending off the sleeve member 200' are two parallel arms, the upper arm being designated by numeral 206 and the lower arm by numeral 206'. The said arms 206 and 206' with the sleeve member 200' form a clevis for the journaling of spindle 204, the said spindle 204 penetrating upper and lower plates 26 and 27 through slots therein. Affixed to the projecting upper end of spindle 204 is a sprocket which is connected to another sprocket 201 by means of a chain 202, the sprocket first mentioned being designated by numeral 203. Sprocket 201 is affixed to the upper end of spindle 200. Spindle 204 mounted in the above mentioned clevis has therearound a roller 205. Since the sleeve member 200' is free to rotate within the bearings afforded by the perforations in plates 26 and 27, and since the spindle 200 therein is free to rotate, the clevis assembly is capable of being moved through a small arc without interfering with the constant rotation of roller 205 and the assembly comprising spindle 204, sprocket 203, chain 202, sprocket 201, spindle 200 and pinion 198. Upper arm 206 is provided with a perforated extension in which is anchored contractile spring 207, the said spring being affixed to upper plate 26 as indicated by numeral 208 in Figure 3. The tension of spring 207 pulls the clevis assembly and with it roller 205 so that the said roller enters the chamber formed by plates 160, 161 and 162 through an opening between plates 161 and 162. The said clevis assembly is maintained in its normal position so that roller 205 does not project within the opening between plates 161 and 162 by lever 209, one end of lever 209 bearing against upper clevis arm 206, the other end bearing against another lever 210, the lever 209 being pivoted intermediate the length thereof on a short stud projecting from upper plate 26. Lever 210 is pivoted intermediate the length thereof on a similar stud projecting from upper plate 26. The power arm of lever 210 resting against a cam 211 acts as a follower therefor. With rotation of plate cam 211, the follower arm of lever 210 will momentarily fall in the depression in the

periphery of said cam, the depression being designated by numeral 212, thereby allowing the clevis assembly to be operated by spring 207 and causing roller 205 to project into the opening between plates 161 and 162.

Numeral 218 designates a small flat shoe projecting through an orifice therefor in upper plate 26, the said shoe being maintained in frictional contact with the upper edges of sheets of sensitized material which have come to rest within the chamber 160, 161, 162. Shoe 218 is affixed at its forward end to an end of spindle 217, while at the other end of the said spindle is a short vertical arm 219 affixed thereto. The spindle 217 is mounted transversely above and parallel with upper plate 26 by bracket 220. The upper end of vertical arm 219 is orificed to anchor a contractile spring 221 extending from upper plate 26, the tension of the spring serving to depress shoe 218 by means of the bell-crank structure above 20 described. Where the frequency with which sheets of exposed sensitized material are deposited on the conveyer 145 is greater than the frequency with which sheets of exposed sensitized material are removed from the chamber formed by plates 160, 161 and 162, it being understood at this time that the said plates in conjunction with upper and lower plates 26 and 27 constitute the chamber proper, there will occur within the aforementioned chamber a vertical stacking of 30 the sheets of the exposed sensitized material across the width of said chamber. Owing to the fact that the camera unit deposits the sensitized sheets of material in the form of a resilient semi-cylinder as has been before mentioned with the 35 convex surfaces thereof resting on the conveyor 145, the said sheets of sensitized material after passing through the sets of rollers 164-167, 170-173, and 175-28 superpose themselves in chamber 160, 161 and 162 with the unsensitized 40 faces thereof facing the roller 205.

The frictional engagement of shoe 218 with the upper edges of the stacked sheets aforementioned retains the said sheets in chamber 160, 161 and 162 so that roller 205 when in operative position 45 or in the opening between plates 161 and 162 advances only the outermost sheet to a position of engagement between rollers 188 and 185. It will be noted at this point that roller 188 is driven solely by its frictional engagement with roller 50 55 55 60 65 65 70 75 75 80 85 85 90 95 100 105 110 115 120 125 130 135 140 145 150 155 160 serves to open the two jaws of clip 58, while upon the release of the said pressure the jaw members of the clip close and thereby grip the upper longitudinal edge of a sheet of sensitized material. 5 Extending from the rear edge of upper plate 26 and affixed thereto is a longitudinally extending arm 223 curved near the free end thereof so that the end of said arm 223 serves as a support for arm 60 when clip 58 is opened, by the forward 10 pressure of lever arm 227. Adapted to bear against lug 62 is a lever pivoted on a short stud 225, said stud being affixed and projecting upwardly from upper plate 26. The said lever comprises a load arm 227 and a power arm 224, the latter arm terminating in a mounted roller 226, the said roller being adapted to cooperate with plate cam 35, the said cam being affixed to the upper end of a shaft 213 at a point directly above cam 211 which latter is likewise affixed to shaft 20 213. The cams 35 and 211 are both positioned above upper plate 26. Shaft 213 is vertically disposed and is journalled near the upper end thereof in an orifice in upper plate 26, said shaft intermediate the length thereof being journalled in a 25 horizontal support member 251, while at the lower end the said shaft is journalled in an upright support 36. Affixed to shaft 213 near the lower end thereof is a worm gear 214 meshing with a worm 215 on main driving shaft 34. Identical to 30 the ratio existing between worm gear 76 and worm 77 is the ratio existing between worm gear 214 and worm 215, the said ratio being 40 to 1. It will therefore be seen that synchronization will take place between the arms 60 in the positioning 35 thereof and the opening and closing of the clip 58 and the ejecting of a sheet of sensitized material from the sensitized material feeding mechanism into the clip 58, since all of these operations derive the power and timing therefor from the two 40 worms on shaft 34.

The sequence of the clip loading operation is as follows. One of the arms 60 carrying the clip 58 comes to an intermittent rest directly opposite the sensitized material ejecting rollers 188 and 45 185; the movement of plate cam 35 causes load arm 227 to bear against clip operating lug 62 thereby opening the jaw members of the said clip; while the jaw members of the said clip are retained in their open position, cam 211 through its 50 related mechanism allows a momentary contact between roller 205 and a sheet of sensitized material thereby forcing the same in contact with the rollers 188 and 185, which latter in turn eject the said sensitized material between the open 55 jaws of clip 58. Directly below the jaws of clip 58 is a deep narrow trough or guideway U-shaped in cross-section and supported by a horizontal plate member number 37, the said trough being formed by side walls 229 and 230 being joined together at the base thereof. Extending from the upper longitudinal edge of wall 230 is an acutely diverging plate 231 as best seen in Figure 4 of the accompanying drawings. The said trough serves to maintain the sheet of sensitized material 60 which has been deposited therein in proper position for the gripping of the upper edge thereof by the jaw members of clip 58. The jaw members of clip 58 are allowed to close by the removal of pressure from operating lug 62 caused by the 65 withdrawal of arm 227, the latter withdrawal being effected by the further rotation of cam 35. Although the rotation of spider hub 56 and the extending arms 60 is counter-clockwise, the rotation thereof is not hindered by the projecting 70 arm 223 because rotation occurs when the spider 75

hub 56 is in an elevated plane thereabove, the said hub dropping down for the loading operation with one of the arms 60 thereon resting to one side of arm 223. In the loading position, the manipulations of loading occur immediately 5 after the high speed oscillatory cam 78 has ceased to contact the lever 63 for agitation purposes.

After a sheet of sensitized material has been gripped by jaws of the clip 58, sleeve 53 is raised, thereby carrying with it clip 58. When the spider 10 hub 56 reaches its uppermost position, it is given a 36 degree counter-clockwise rotation, as has before been stated. After the 36 degree movement has been completed, the clip 58 carrying a sheet of sensitized material will be positioned over 15 tank 124 containing the developing solution. Spider hub 56 is now automatically lowered owing to the cooperation of follower arm 14 and cam surface 65, the said lowering resulting in the immersion 20 of the already mentioned sheet of sensitized material within the tank 124. After the said sheet has been immersed, cam 18 is allowed to contact lever 63 for agitation purposes, said agitation continuing for approximately 45 seconds. For the next ensuing 5 seconds approximately, the print remains stationary in tank 124 and during such period of time a clip 53 on an arm 60 is being loaded opposite the feeding mechanism. Thereafter the aforesaid raising 25 and lowering of sleeve 53 is repeated consuming 30 approximately 10 seconds. The process is then repeated in a counter-clockwise direction, the sheet being consecutively rotated for immersion and immersed in tanks 125, 126, 127, 128, 129, 130, 131, and 132. It will be seen by reference to 35 Figure 3 that each of the clips 58 on the arms 60 is capable of carrying a separate sheet of sensitized material and each of the said sheets will be in a different stage of development at any given time. After a sheet of sensitized material has 40 been immersed in the last tank of the series, namely, tank 132, it is moved to a position opposite the feeding mechanism but in a plane above the mouth of the trough having side walls 229 and 230 as best seen on Figure 4. As the sleeve 45 member 53 is lowered at this point of time, the sheet of sensitized material being thereby lowered, the lower longitudinal edge of said sensitized sheet strikes against two flat downwardly curled resilient guides 228. The said guides are 50 fixed to the upper portion of wall 229 and extend upwardly therefrom. In striking against said guides 228, the sheet of sensitized material is deflected so that the same slides downwardly on the aforementioned acutely diverging plate 231. 55 It will be noted at this point that clip 58 in its lowermost position has forced or compressed guides 228 to one side so that the jaws of clip 58 may descend within the upper longitudinal mouth of the trough of walls 229 and 230. The 60 guides 228 compressed as above described are shown in Figure 4. It will now be seen that when the jaws of clip 58 are separated by the feeding and clip loading mechanism as has been described hereinbefore, the paper held by said clip and already developed is discharged along diverging plate 231. Sufficient time is provided by the synchronization of the feeding and loading mechanism so that there is a sufficient interval between the opening of the jaws of clip 58 and the 70 instant when an undeveloped sheet of sensitized material is ejected into the trough of walls 229 and 230 for the discharge of a previously developed sheet of sensitized material.

A developed sheet of sensitized material hav-

ing been released along diverging plate 231 is now ready to go through the process of drying after which the said material discharges from the developing unit as a finished print.

5 The drying structure is mounted in the developing unit within two spaced, vertical and transverse plate members 38 and 39, the said plate members being integral and projecting upwardly from a base plate 38' resting on the floor of the 10 main frame work. These plates 38 and 39 are irregular in shape and extend upwardly to a point just below shelf 21 and inwardly toward the longitudinal axis to a point just beyond shaft 34. At the intersection of the vertical inner edge and 15 the upper horizontal edge of plates 38 and 39, are two diagonally projecting arms 39', said arms being joined by and serving as a support for a horizontal plate 37, said plate 37 in turn serving as a support for the trough 229, 230. Numeral 20 232 is a roller mounted upon a spindle 233, said spindle being journaled in orifices in arms 39' and situated directly below acutely diverging plate 231. The forward end of spindle 233 projects beyond the arm 39' and has affixed thereto 25 a sprocket 234 which is connected by chain 235 to a sprocket 236 as best seen on Figure 2. A roller 252 is mounted upon a spindle 237, the said spindle being situated at the base of the arms 39' and being journaled in orifices of transverse 30 plate members 38 and 39. The forward end of spindle 237 projects beyond plate member 39 and has affixed thereto the aforesaid sprocket 236. The rear end of spindle 237 projects beyond plate 38 and has affixed thereto a collar 238' and a 35 sprocket 238, the said sprocket 238 being connected by chain 239 to a sprocket 240 which is keyed to main power transmission shaft 34. The ratio existing between sprocket 238 and sprocket 240 is four to one. Numeral 241 designates a roller 40 mounted upon a spindle, the said spindle being trunnioned in bearings mounted in the upper ends of two juxtaposed levers 242. The said levers 242 are pivotally mounted upon a spindle 243 intermediate the height thereof. The spindle 243 is journaled in orifices in the arms 39' projecting therethrough and it is to these projections that the levers 242 are affixed outside of the arms 39' as best seen in Figure 4. Affixed to a point 45 on levers 242 are contractile springs 249, the said springs being anchored to plates 38 and 39 at a point proximate to the said levers 242. Springs 249 by their contraction are adapted to force a pair of rollers 244 which are mounted on the lower ends of levers 242 in contact with plate 50 cams 245, the said cams being affixed to a horizontal and longitudinal shaft 246 at points immediately forward of plate 39 and immediately rearward of plate 38. The said shaft 246 extends beyond that forward cam 245 and penetrates an orifice in horizontal support member 55 251 in a depending flange therefrom, the said shaft 246 terminating in a bevel gear 247 affixed thereto. Bevel gear 247 meshes with a bevel gear 248, the latter being keyed to the vertical shaft 213 at a point immediately below horizontal support member 251. Numerals 254 and 255 designate 60 rollers mounted on spindles, the latter being trunnioned in brackets, the said rollers being positioned above circular trough 121 and adjacent a side panel of the developing unit frame work as best seen in Figure 4, the brackets above mentioned not being shown in the drawing. 256 is a roller mounted on a spindle, the said spindle being trunnioned in orifices at the upper portions of the outer edges of plate members 38 and

39. 253 represents a flat belt which is in contact with and driven by roller 252, the said belt 253 passing over rollers 254 and 255 and under roller 256, rollers 254, 255 and 256 serving as idlers and also for changing the direction of travel of the 5 aforementioned belt 262 extending off the outer face of a side panel of the frame work of the developing unit and opposite roller 255. Receptacle 261 is adapted to receive dried prints from belt 253 as it passes over roller 254 through an 10 opening in the side panel. Numeral 257 designates a casing for the heating element 258, the latter being positioned within the casing by insulating material 259. Casing 257 is substantially L-shaped and is supported at the upper end thereof immediately above the roller 254, the said casing 257 being provided with a depressed portion 260 so that the same does not interfere with outer wall 122 of trough 121.

It will now be seen that a developed sheet of 20 sensitized material in passing from acutely diverging plate 231 will come in contact with roller 232, the said roller revolving at approximately eleven revolutions per minute. At this time, owing to the synchronization of lever arms 242 25 through cams 245 by way of shaft 213 with the arm 227 roller 241 will be brought into contact with roller 232, the wet print or sheet of sensitized material thereby being drawn downwardly therebetween. The cooperation of rollers 232 and 241 30 serves to wring out excess water from the sheet of sensitized material; the said excess of water draining downwardly through the inclined perforated plate 250 being carried off by means not shown in the drawing. The perforated plate 250 35 is affixed to the inner surfaces of the arms 39' at rollers 232 and 252 and directly above spindle 243. In addition to the wringing performed by rollers 232 and 241, this same pair of rollers at the same time feeds the wrung sensitized material onto the moving belt 253, the said belt traveling in the direction indicated by the arrow in Figure 4. Belt 253 carries the sensitized material along with it in proximity with the heated casing 257 at the lower surface thereof to the 40 point of ejection at roller 254 as before described. 45

In order that the heat generated by the heating element 258 and in order that the entire developing unit shall continue to function until all of the separate sheets of sensitized material that 50 have been deposited upon conveyer 145 are completely finished and ejected into receptacle 261, the developing unit is provided with a timing mechanism located on intermediate shelf 21 forwardly thereof and to one side of the feeding 55 mechanism to clips 58.

Attached to vertical shaft 213 directly above horizontal support member 251 is a bevel gear 334 meshing with another bevel gear 333, the latter being affixed to the rear end of a short longitudinal shaft 332. Shaft 332 penetrates near its rear end an upwardly extending flange of horizontal support member 251 and penetrates near the forward end thereof a support 52 depending from the lower surface of plate 27. Affixed to the 60 forward end of shaft 332 is a sprocket 331 connected by a chain 330 to a sprocket 329, the said latter sprocket being affixed to the forward end of a short longitudinal shaft 319. Shaft 319 is trunnioned at the rear end thereof in an upright 65 support member 320, the said support 320 being affixed to and projecting upwardly from the timing unit base plate 263, the latter being supported by intermediate shelf 21. Shaft 319 is supported near the forward end thereof by an 70

upright support member 321, said support being similarly mounted as support 320. Affixed to shaft 319 and behind support 321 is a plate cam 322. Numeral 324 designates a mercury switch connected in series with the electrical heating element 258 of the drying mechanism, said switch being mounted upon a forwardly projecting trunnion 325, the said trunnion being mounted in an upward extension of upright support member 321. Switch 324 is provided with a short stud projecting from the front face thereof, the stud being designated by numeral 323, the said stud resting upon plate cam 322. Numeral 327 designates a small contractile spring which is connected to the lower edge of switch 324 through an eye 326, the other end of said spring being anchored near the bottom of upright 321 by screw 328. Affixed to shaft 319 and near the rear end thereof is a plate cam 318, the said cam being in frictional engagement with a roller 317 which acts as a follower therefor. Roller 317 is trunnioned in the lower end of power arm 316 which, together with load arm 313, constitutes a lever pivoted intermediate the length thereof on a stud 314 projecting from an upright 315. Numeral 311 designates a link being pivotally connected to the upper end of load arm 313 by means of a short machine screw 312 and being similarly connected to the upper end of a radial arm 307 by the machine screw 308, the said radial arm 307 being rotatable and unkeyed about shaft 266. Pivoted by means of a screw 303 and proximate the upper end of radial arm 307 is a pawl 302 the operative tooth thereof being forced into engagement with peripheral ratchet teeth 294 of a disc member 293 by the contraction of a small contractile spring 305 which latter is affixed to an upwardly extending projection 304 of pawl 302 and anchored immediately below machine screw 308 on radial arm 307 at a point indicated by the numeral 306.

To one side of disc 293 and in the same vertical plane is an upright support member 301 projecting from plate 263. At the upper end of the said upright 301 is a small orifice 310 serving to anchor one end of a contractile spring 309, the other end of said spring being affixed to the upper end of radial arm 307. Spring 309 serves by means of link member 311 and lever 313—316 to force roller 317 into frictional engagement with plate cam 318. Numeral 296 indicates an operative tooth of a pawl member pivotally mounted near the lower end of upright 301 by means of a machine screw 297, the said operative tooth being held in engagement with the ratchet teeth 294 through the contraction of contractile spring 299, the said spring being affixed by hooking into an orifice 298 in the lower end of pawl arm 296 at one end thereof and at the other end being anchored to the lower end of upright 301 by means of screw 300.

The disc member 293 rotates about but is not keyed to a shaft 266, the said shaft being affixed at the forward end thereof in the upper end of a vertical upright 264, the latter extending from plate 263, while the said shaft is similarly affixed at the rear end to upright 264. Perpendicularly and rearwardly projecting from disc 293 and concentrically disposed proximate the edge thereof 70 is a plurality of pins 295. Adjacent the rear face of disc member 293 and spaced therefrom is a spiral spring 276 concentric with shaft 266, the said spring being affixed at the inner end to shaft 266 by a machine screw 277, while at the outer end thereof the said spring is affixed to a

short stud 275. Stud 275 is affixed to the front face of an annular plate 267 adjacent the edge thereof. Annular plate 267 forms a portion of a sleeve member for shaft 266, the said sleeve member being spaced from the rear face of disc 5 293 to permit the position of spiral spring 276 therebetween as best seen in Figure 10. The sleeve member comprises an annular plate portion 267, a reduced spiral cam surface portion 274 having a rearwardly projecting lug 273, a 10 sleeve portion proper 268 having two spaced expanded collars thereon 269 and 270 forming an annular channel 271 therebetween. The sleeve member is adapted to reciprocate along the shaft 266, the said reciprocation being caused by the 15 movement of a bifurcated control arm 336, the latter being pivotally mounted by the penetration therethrough of screw 337 fixed in the upper end of a short upright 338 projecting from plate 263 as shown in Figure 8. Control arm 336 at the 20 bifurcated portion 335 engages with channel 271 of the sleeve member thereby causing the sleeve to reciprocate therewith. Numeral 272 designates an expansive and helical spring concentric with shaft 266 and intermediate collar 270 and 25 upright 264.

Numeral 281 designates an upright projecting from plate 273 and having a curved arm 283 extending therefrom. Numeral 278 represents a mercury switch in series with the circuit of 30 motor 30 and is pivotally mounted by a pin 280 journaled in the upper end of upright 281. From the front face of switch 278 is a forwardly projecting lug 279, the said lug being adapted to bear against and act as a follower for the cam 35 274. Projecting rearwardly from a lateral extension of the front face of switch 278 is a short stud 285 adapted to cooperate with a pivotal lever 284 having at the top thereof a latching recess for the said stud. Lever 284 is 40 pivotally mounted to the outer extremity of arm 283 by screw 286. Projecting forwardly and perpendicularly from the lower end of lever 284 is a stud 287 adapted to be struck by the lug 273 extending off the cam surface portion 274 of the 45 sleeve member for shaft 266. 291 represents a stud projecting forwardly and perpendicularly from the front face of annular plate 267 being intermediate stud 275 and the edge of plate 267, the said stud 291 being adapted to engage with 50 in the interstices of pins 295 when the sleeve portion 268 is in its forward reciprocated position. Stud 291 is also adapted to strike against an upright lug 292 which forms a stop therefor thereby controlling the rotation of sleeve 268. 55 Upright lug 292 projects from plate 263.

343 represents a solenoidal magnet having an armature 342 adapted to be drawn therein when the solenoid is energized. The armature 342 is pivotally attached at the forward end thereof by means of a machine screw 341 to the rear end of a link 340, the said link being pivotally attached to lever 336 by penetrating a slot therein and turning about machine screw 339 as best seen in Figure 8. 288 is a contractile helical spring 65 being affixed to the lower arm of lever 284 at orifice 289 and being anchored to the upper surface of lever 336 by a machine screw 290.

Now will be described the operation of the timing device. Since shaft 213 revolves at the 70 rate of approximately one R. P. M. by virtue of uniformed ratio gearing, shaft 319 in turn revolves at approximately one R. P. M. The cam 318 through lever 313—316, link 311, arm 307 and pawl 302 causes disc 293 to rotate one thir-

tieth of a revolution in the direction of the arrow on Figure 7 approximately every sixty seconds. The consecutive and intermittent rotational positioning of disc 293 is maintained by the pawl tooth 296 engaging with teeth 294 thereby serving as a pawl and ratchet arrangement. Sleeve member 268 being free to rotate about fixed shaft 266 because of its connection with spring 276 tends to revolve in a counter direction to disc 293. Spring 272 forces the sleeve member 268 forward along shaft 266 so that lug 291 engages disc 293 between two adjacent pins 295. The cam surface 274 is so arranged on sleeve member 268 that the said cam surface elevates lug 279 and motor switch 278 therewith to the "on" position of the said switch when the lug 291 strikes against the stop 292. It will now be seen that when solenoid 343 is energized, the latter taking place simultaneously with the depositing 20 of an exposed print on conveyor 145, armature 342 and link 340 will cause lever 336 to move rearwardly thereby causing a rearward movement of sleeve 268 and a consequent compression of spring 272 and also the disengagement of lug 291 from disc 293. The rotation movement of sleeve 268, now being unrestricted since lug 291 is out of mesh with pins 295, the unwinding of spring 276 causes cam 274 to elevate switch 278 to its "on" position as just above described. 30 When switch 278 is elevated to its horizontal "on" position, pin 285 latches with lever 284 serving to maintain the switch in its horizontal "on" position. The electrical circuit to the motor 30 now being closed, the entire developing 35 unit commences to function, shaft 319 rotating as a part of the developing unit. Since the solenoid 343 is energized for only a few seconds, simultaneous with the dropping of an exposed sheet of sensitized material on conveyor 145, 40 when said solenoid 343 is deenergized, armature 342 and link 340 move forward owing to the pressure exerted by expansive spring 272 thereby moving sleeve 268 forward so that lug 291 engages disc 293. 45 Shaft 319 in rotating causes cam 322 to intermittently elevate drier switch 324 to its horizontal on position, the intermittent on and off periods of switch 324 being for approximately thirty second intervals. The shaft 319 in rotating also causes disc 293 to rotate by means of cam 318 as above set forth, the said disc 293 being now engaged with sleeve 268 because of the de-energization of the solenoid 343. By such engagement disc 293 thereby rotates sleeve 268 so 50 that lug 273 will after approximately fifteen minutes (one-half revolution of sleeve 268) strike pin 287 thereby disengaging the latching lever 284 from pin 285. Said disengagement allows the contraction of spring 282 to pull motor switch 278 to its inclined off position with lug 279 resting upon the lowermost surface of cam 274. It is now to be noted that at this position of lug 273, at the time of striking pin 287, valves 115 and 108 are in their closed position as before 55 described, and cam 322 is in such position that switch 324 is in its off position. Now it can be seen that with each energization of solenoid 343, the entire cycle above described is repeated so that regardless of the number of consecutive exposures deposited on conveyor 145 or the frequency of the exposures, the developing unit will 60 continue to run for a period of approximately fifteen minutes from the last exposure.

I claim:

1. In an automatic developing and finishing machine for exposed sensitized material, a cas-
ing therefor having front, side, rear and bottom walls, an upper wall having a movable aperture for the receipt of exposed sheets of sensitized material, a feeder continuous with the path of travel of the said movable aperture to carry said sheets to the developing apparatus, said aperture being independently movable with relation to said feeder.
2. In a chamber for developing and finishing exposed sensitized material, an upper wall having a movable aperture.
3. In a chamber for developing and finishing exposed sensitized material, an upper wall having a movable aperture, feeding means to carry said sheets to a predetermined position.
4. In an automatic developing and finishing machine for exposed sensitized material, a casing therefor having front, side, rear and bottom walls, an upper inclined wall having a movable aperture for the receipt of exposed sheets of sensitized material, an inclined feeder stationary with relation to and below the path of travel of the said movable aperture and continuous with the path of travel of the said movable aperture to carry said sheets to a predetermined position.
5. In combination with a movable camera, a casing for a developing and finishing machine, the said casing having front, side, rear and bottom walls, an upper wall having a light-proof and movable aperture for the receipt of exposed sheets of sensitized material from the said movable camera, a feeder to carry said sheets to a predetermined location, said feeder being stationary with relation to and continuous with the path of travel of the said movable aperture.
6. In combination with a movable camera, a casing for a developing and finishing machine, the said casing having front, side, rear and bottom walls, movable means of light-proof communication between said movable camera and said casing, a feeder stationary with relation to the path of travel of said movable means and adapted to receive exposed sheets from the said camera in any displaced position thereof and to advance the said sheets to the developing apparatus.
7. In combination with a movable camera, a casing for a developing and finishing machine, supporting means on said casing for the said camera, means of light-proof communication between said movable camera and said casing, a feeder adapted to receive exposed sheets from the said camera in any displaced position thereof and to advance the said sheets to the developing apparatus.
8. In combination with a movable camera, a casing for a developing and finishing machine, tracks for said camera supported by said casing, means of light-proof communication between said movable camera and said casing, a feeder adapted to receive exposed sheets from the said camera in any displaced position thereof and to advance the said sheets to the developing apparatus.
9. In combination with a movable camera, a casing for a developing and finishing machine, inclined tracks for said camera supported by said casing, means of light-proof communication between said movable camera and said casing, a feeder adapted to receive exposed sheets from the said camera in any displaced position thereof and to advance the said sheets to the developing apparatus.
10. In an automatic developing and finishing machine for exposed sensitized material in com-

- bination with a movable camera, a casing for the said machine, an upper wall of said casing having a movable aperture therein in communication with the said camera, a feeder continuous with the said movable aperture, means to automatically and successively develop and finish sheets of exposed sensitized material advanced from the said feeder.
11. In an automatic developing and finishing machine for exposed sensitized material in combination with a movable camera, a casing for the said machine, an upper wall of said casing having a movable aperture therein in communication with the said camera, a feeder continuous with the said movable aperture, means to automatically and successively develop and finish sheets of exposed sensitized material advanced from the said feeder, means to dry the said finished sheets, and feeding means to the said drying means.
12. In an automatic developing and finishing machine for exposed sensitized material in combination with a movable camera, a casing for the said machine, an upper and inclined wall of the said casing having a movable aperture therein in communication with the said camera, a feeder continuous with the said movable aperture and being in parallelism with the said upper wall, and means to automatically and successively develop and finish sheets of exposed sensitized material advanced from the said feeder.
13. In a chamber for developing and finishing exposed sensitized material, an upper wall having a movable aperture, a camera disposed adjacent said aperture and movable therewith.
14. In combination: a casing adapted for the reception of exposed sensitized material, a movable upper wall on said casing provided with an aperture, a camera support having an orifice therein disposed with relation to said aperture so that a passage for said material is afforded through said aperture and said orifice, said support being movable jointly with said movable wall and movable independently of said casing.
15. In combination: a chamber for the reception of exposed sensitized material, an upper wall having a movable aperture, a camera support having an orifice therein disposed with relation to said aperture so that a passage for said material is afforded through said aperture and said orifice, said support being movable jointly with said aperture and being movable independently of said chamber.
16. In combination: a chamber for the reception of exposed sensitized material, said chamber being adapted for use with a movable camera, an upper wall in said chamber having a movable aperture, a support for said camera having an orifice therein disposed with relation to said aperture so that a passage for said material is afforded through said aperture and orifice, said support being movable jointly with said aperture and movable independently of said chamber, means to adjust the position of the camera independently of said support.
17. In a chamber for the receipt of exposed sensitized material, an upper wall having a movable aperture, said wall including a flexible light-proof curtain.
18. In a device of the class described: a casing adapted for the reception of exposed sensitized material, said casing having an opening therein, a movable camera support adapted for travel adjacent said opening, flexible means forming a light-proof connection between said casing and said movable support.
19. In a device of the class described: a casing adapted for the reception of exposed sensitized material, said casing having an opening therein, a movable camera support adapted for travel adjacent said opening, a curtain forming a light-proof connection between said casing and said movable support, and means to take up or release the curtain as the position of the support is varied.
20. In combination with a movable camera, a casing for the reception of exposed sensitized material ejected by said camera, movable supporting means for said camera forming a light-proof connection between the camera and the casing, and supported by the said casing.
21. In combination with a movable camera, a casing having an inclined upper wall and adapted for the reception of exposed sensitized material ejected by said camera, and movable supporting means for said camera forming a light proof connection between the camera and the casing, and supported by the upper wall of said casing.
22. In a chamber for the reception of exposed sensitized material, an upper wall having a movable aperture, a camera disposed adjacent said aperture and movable therewith, and means to move said camera.
23. In a chamber for developing and finishing a plurality of exposed sheets of sensitized material, an upper wall having a movable aperture, a loading magazine for said sheets located at a fixed and predetermined position in said chamber, and feeding means to carry said sheets to said magazine.
24. In combination with a movable camera, a casing for a machine adapted to develop and finish a plurality of separate exposed sheets of sensitized material, an upper wall in said casing adapted by means of a movable aperture therein to receive sheets from said camera, accumulating means for the collection of said sheets located at a predetermined position in said casing, and a feeder to carry said sheets to said accumulating means after the sheets have been received by the casing from the camera, said feeder being characterized by the fact that it is stationary as a unit with relation to, and continuous with the path of travel of the said movable aperture.
25. In combination: an automatic photographic developing machine for treating a plurality of exposed sheets of sensitized material, accumulating means for collecting said sheets, conveying means for transporting said sheets from the point of deposit thereof within the machine to the said accumulating means, a mechanism in the said developing machine and adapted to receive sheets at predetermined intervals, means to consecutively eject single sheets from said accumulating means into said mechanism at said predetermined intervals.

SAMUEL HERSHBERG.
